SIDE WALL SAMPLE TAKING APPARATUS

Maurice Mennecier, Houston, Tex., assignor to
 Schlumberger Well Surveying Corporation,
 Houston, Tex., a corporation of Delaware

Application September 10, 1947, Serial No. 773,146

11 Claims. (Cl. 255—1.4)

1

The present invention relates to side wall sample takers for use in bore holes drilled into the earth. More specifically, it relates to a new and improved side wall sample taker which greatly facilitates the taking of cores from harder formations, such as limestones, for example, although it is not limited to such use.

The applicant's prior patent application Serial No. 669,923, filed May 15, 1946, for Side Wall Sample Taker, now Patent No. 2,558,452, is addressed to sample taking apparatus which is characterized by simplicity and reliability. That apparatus comprises generally a body member adapted to be anchored in a bore hole and having drilling and sampling means slidably mounted therein for movement towards and away from the side wall of a hole. The latter means is adapted to be driven by a motor in the apparatus, the weight of which is applied to the drilling and sampling means during the drilling operation. By means of this apparatus, a plurality of cores can be taken on a single trip into a bore hole. However, the successive cores are all stored in the drilling and sampling means so that the total number that may be taken is limited by the length of the latter means.

The principal object of the present invention, accordingly, is to provide new and improved sample taking apparatus, the sample taking capacity of which on a single trip into a bore hole is considerably greater than that of the sample taking apparatus used heretofore.

Another object of the invention is to provide new and improved sample taking apparatus of the above character, the capacity of which on a single trip into a bore hole is not limited by the length of the drilling and sampling means.

A further object of this invention is to provide new and improved side wall sampling apparatus of the above character which includes a core receiving magazine and means for extracting a core from the drilling and sampling means and conveying it to the magazine.

Another object of this invention is to provide new and improved sampling apparatus of the above character in which marking means is provided for positively identifying the various cores conveyed to the magazine.

The objects of the invention are attained by providing drilling and sample taking means having means for extracting the core therefrom after it has been cut and broken off the formation. The extracted core is adapted to drop into suitably shaped conveyor means which directs it to a core receiving magazine. Means are also

2

provided for automatically inserting marking means between successive cores to enable them to be readily identified when the apparatus is raised to the surface after a core taking trip has been made in a bore hole.

The invention may be better understood from the following detailed description of a representative embodiment, taken in conjunction with the accompanying drawings, in which:

10 Figure 1 is a view in vertical section through sample taker apparatus constructed according to the invention when it is in the inoperative or retracted position, illustrating the relative positions of the parts as it is being moved along a bore hole;

Figure 2 is an enlarged view in perspective showing the details of the drilling and sampling means, its drive assembly, and the core breaker apparatus of Figure 1;

15 Figure 3 is a view in vertical section through the apparatus after it has been anchored in the bore hole, but before the sampling operation has been begun;

Figures 4A, 4B and 4C are enlarged views of 25 the anchor retaining and releasing mechanism, Figure 4A illustrating the position of the parts when the anchor is held within the body of the tool as in Figure 1, Figure 4B showing the mechanism ready to release, and Figure 4C illustrating in longitudinal section the position of the parts after the tool has been anchored in the bore hole as shown in Figure 3;

Figures 5A and 5B are partial plan views taken 30 along line 5—5 of Figure 3, looking in the direction of the arrows, showing the gearing in greater detail for the Fig. 4A and Fig. 4B positions, respectively;

Figure 6 is a view in vertical section similar 35 to Figures 1 and 3, but showing the apparatus after the core drill has penetrated the formation and the core has been broken and is ready to be retrieved;

Figure 7 is an enlarged view in perspective of 40 the drilling and sampling means, the drive assembly and core breaker apparatus of Figure 6, after the core breaker has functioned;

Figure 8 is a schematic wiring diagram which 45 also illustrates the arrangement for signaling the operator when the tool has been anchored, and when the core drill has penetrated the formation to the desired depth.

Referring to Figure 1, a side wall sample taker 50 is shown comprising an elongated cylindrical body 10 having an upper portion 11 and a lower portion 12 terminating in a rounded closure

member 13. The upper cylindrical portion 11 of the body 10 has formed therein a chamber 14 which is closed off at its lower end by a transverse partition 15 and which has an opening at the upper end consisting of a bore 16 of reduced diameter. Within the cylindrical portion 11 is disposed a water-tight housing 17 containing a conventional type motor 18 and a speed reduction gear 20. The motor 18 is energized and controlled in any suitable manner as by a source of electrical energy B, switch S and ammeter A at the surface of the earth, connected to a conductor C in the supporting cable 30, as schematically shown in Figure 8.

Above the housing 17 is disposed a head 29 which is adapted to be slidably received within the bore 16 and to which the supporting cable 30 is secured in the usual manner. A pin 31, secured to the upper body portion 11, extends into a longitudinal keyway 30a in the housing 17 and permits the housing 17 to slide vertically, but prevents it from rotating with respect to the cylindrical body 10.

The mechanical output of motor 18 is transmitted from the shaft 19 and through the speed reduction gear 20 to a shaft 21 which extends through a transverse partition 22 forming a lower water-tight closure for the housing 17. Any suitable gear reduction ratio may be used but a ratio of 5 to 1 has been found satisfactory when the motor 18 operates at 3500 R. P. M.

Rotary motion of the shaft 21 is transmitted through a spring loading or torque spring assembly 26 to a main shaft 27. A flexible sleeve-like member 24 of rubber or other suitable material is positioned about the spring assembly 26 and is connected at its upper and lower ends to the transverse partition 22 and to a partition 36, respectively. The partition 36 is adapted to slide freely within the cylindrical portion 11 and is secured by a perforated tubular member 24a to the partition 22.

The bore hole fluid is prevented from reaching the torque spring assembly 26 and the motor 18 by any suitable means such as a packing gland 23, for example. The bore hole liquid has access to the chamber 14 through the passages 25 formed in the body portion 11 and the sleeve-like member 24 is filled with a suitable liquid such as oil, for example. With this construction, the pressures on opposite sides of the sleeve-like member 24 are substantially equalized so that the packing gland 23 may be designed for a low differential pressure and exerts a relatively low frictional torque on the shaft 27.

The shaft 27 passes through the transverse partition 15 and is connected to the universal joints 28 and 32 which permit power to be transmitted to the drilling and sampling means 34 as the latter advances downwardly and outwardly towards the side wall of the bore hole. The universal joint 32 is connected to a gear 36 rotatably mounted in a block 33. The gear 36 engages a ring gear 37 formed on the periphery of the drilling and sampling means 34 which is also rotatably mounted in the block 33 but is not movable axially therein.

In accordance with the usual practice, the drilling and sampling means 34 is provided with a bit 35 at its forward end, which may be set with diamonds or other suitable hard materials. Also, its outside diameter is preferably made larger than the outside diameter of the drilling and sampling means 34 so as to provide space for the exit of the drill cuttings. The drilling

and sampling means 34 is also preferably fitted with suitable means such as springs, for example, (not shown) which constitute a core catcher for retaining a core therein, as disclosed in my above-identified copending application.

The block 33 is pivotally connected at 103 to a pair of parallel arms 40 (Fig. 2) formed on a framework 39 mounted on a rigid rod 38 which extends through the transverse partition 15 (Fig. 1) and is rigidly secured in any suitable manner to the transverse sliding partition 36.

The block 33 is normally releasably locked within the lower body portion 11 in any suitable manner, as shown in Figure 1. For example, a recess 79 may be formed in the rod 38 which is adapted to receive a latch 78a pivotally mounted at 80 on the body portion 11. The latch 78a has an arm 78 which is adapted to be actuated to release the latch in a manner to be described in greater detail hereinafter.

The block 33 is provided with pins 41 and 42 on opposite sides thereof (the pins on one side only being shown in Fig. 2) which are adapted to be slidably received within the grooves 44 and 43, respectively, (Fig. 7) formed in a pair of parallel guide plates 45. The slots 44 and 43 are so shaped as to permit the block 33 to be moved downwardly and then outwardly in a direction toward the side wall of the bore hole.

As shown in greater detail in Figure 7, each of the guide plates 45 comprises a separate forward portion 95 defining the upper side of the slot 43, and a cooperating rear portion 95a. The forward portions 95 are rigidly secured to the body portion 11 in any suitable manner as by the bolts 94, for example.

The rear portions 95a of the guide plates 45 are preferably rigidly secured together in any suitable manner and are normally retained in assembled relationship by releasable latching mechanism to be described in greater detail hereinafter. They may be provided with vertical slots 104 (Fig. 7) within which pins 105 secured to the body member 11 are adapted to be received. This construction permits the rear portions 95a to move downwardly with respect to the forward portions when the latching mechanism is released.

At the upper end of the rear portion 95a of the left-hand guide plate 45 (Fig. 7) is formed an aperture 106 having an upper edge 107 serving as a cam follower which cooperates with a cam 66 pivotally secured to the body portion 11 at 67. The cam 66 is preferably made longer in one dimension than in a dimension perpendicular thereto, and may be substantially oval in shape, as shown. When in the position shown in Figure 2, it cooperates with the edge 107 to raise the rear portions 95a of the guide plates 45 upwardly so that the pins 105 are at the bottoms of the slots 104. When rotated 90° to the position shown in Figure 7, it permits the rear portions 95a of the guide plates 45 to drop downwardly until the pins 105 rest in the upper portions of the slots 104, as shown in Fig. 7.

For the position of the apparatus shown in Figures 1, 2 and 3, the cam 66 is maintained in the locking position by an arm 71 formed on the frame 39 which serves as a stop for an arm 72 carried by the pivot 67 on which the cam 66 is mounted.

The pivot 67 also carries an arm 70 in which are formed a plurality of teeth 108 (Fig. 2) which are adapted to cooperate with a pawl 69 secured on the frame 39 and biased by a spring 69a, for example, so as to be capable of only counterclock-

wise movement (Fig. 2). The arm 70 and the pawl 69 cooperate in releasing the cam 66 to permit the rear portions 95a of the guide plates 45 to drop downwardly, as will be described in greater detail below.

The apparatus is adapted to be anchored at a given depth in a bore hole by means of cooperating teeth 50 at the upper end of the apparatus and a laterally movable wall gripping member 51 (Fig. 3). The wall gripping member 51 is pivotally mounted at 48 within the lower body portion 12 and has an arm 53 secured by a pin 54 on a link 55. The wall gripping member 51 is provided with a plate 52 which may be secured to the wall gripping member 51 in a number of different positions to increase the effective length of the latter as required to accommodate the apparatus in bore holes of different diameter.

The wall gripping member 51 is adapted to be urged into engagement with the wall of a bore hole by means of a spring 62 which is secured at its lower end to the lower body portion 12 and at its upper end to the lower end of the link 55. The link 55 is connected to a retaining rod 57 terminating at its upper end in a head portion 59 which carries a pair of opposed spring detents 61 and an arm 77 for actuating the latch 78a. The spring detents 61 normally engage a head member 58 provided with opposite flats 49, as shown in Figs. 4A and 4B, which is carried by a rod 56.

The rod 56 is rotatably mounted within a sleeve member 56a secured in any suitable manner to the transverse partition 36. The sleeve member 56a carries a gear segment 60 which is secured by a pin 60a extending through slots 60b in the sleeve member 56a to the rod 56. The gear segment 60 is adapted to engage a cooperating gear 75 mounted on the shaft 27 through a suitable torque spring assembly 76. The gear segment 60 is also adapted to work against a torque spring 64 and a conventional compression spring 63 is interposed between its lower face and a flange 109 on the sleeve 56a. The slots 60b in the sleeve member 56a are preferably made deep enough to permit the gear 60 to be moved longitudinally by the spring 63 out of engagement with the gear 75 when the retainer rod 57 is released. Also, the slots 60b are preferably made wide enough to permit the gear segment 60 to be rotated by the gear 75 through an angle of about 90°. Obviously, any other suitable mechanism may be employed for moving the gear segment 60 only to the extent required to release the retainer rod 57.

Disposed in the lower body portion 12 beneath the block 33 is a core receiving magazine 81 (Fig. 3) of suitable length to receive the desired number of cores. The magazine 81 terminates at its upper end in a funnel-shaped member 82 lying directly beneath the drilling and sampling means 34 when in the position shown in Figure 1. The core receiving magazine 81 is preferably mounted so as to be easily removed from the apparatus at the conclusion of a trip into the bore hole.

Secured to the core receiving magazine 81 is a second magazine 89 containing a plurality of markers which may be spherical balls 83, for example. The balls 83 are normally urged upwardly by a compression spring 84 to engage a member 85 which serves as a stop and which also is adapted to eject a ball through the opening 90 into the core receiving magazine 81 at the time a core is broken off from the formation. This may be accomplished in any suitable manner as by providing an actuator 86 on the movable rear portion

95a of one of the guide plates 45 which is adapted to turn the member 85 against a spring 88 at the time the core is broken off to eject one of the balls 83 into the core receiving magazine 81.

5 The core received within the drilling and sampling means 34 is adapted to be ejected therefrom by any suitable means such as a semi-flexible steel cable 91 secured to the frame 39 and terminating at its other end in a ball or head member 92. The apparatus is preferably so designed that the head member 92 of the ejecting means never completely leaves the interior of the drilling and sampling means 34, as shown in Figure 1, for example.

15 As shown in Fig. 8, the motor 18 is preferably shunted by a resistor 100 in series with a pair of normally open switch contacts 101. The contacts 101 are adapted to be successively closed by suitable actuators 102 and 103 formed on the 20 rod 38, as shown. For example, the actuator 102 may be so located on the rod 38 that it closes the contacts 101 when the rod 38 begins to move downwardly at the initiation of a sample taking operation. The actuator 103, on the other hand, 25 may be so located that it closes the contacts 101 after the sample has been drilled and is ready to be broken off, for example. It will be understood that when the contacts 101 are closed, the 30 current in the conductor C will suddenly change and provide an observable indication on the ammeter A.

Prior to the initiation of a sample taking operation, the several elements of the apparatus are 35 in the position shown in Figure 1. In operation, the apparatus is lowered to the proper depth in the bore hole where a sample is to be taken. The switch S (Fig. 8) is closed and the motor 18 begins to rotate. Because of the presence of the torque springs 26 and 76, however, the shaft 27 40 and the gear 75 do not begin to rotate until some time after the motor has been energized. Preferably, the springs 26 and 76 are so adjusted that the motor 18 will have reached full speed 45 before the shaft 27 begins to rotate. By virtue of this construction, a motor of low-starting torque may be employed. However, if a high-starting torque motor is used, the springs 26 and 76 may be omitted.

When the gear 75 on the shaft 27 finally begins 50 to rotate, it turns the gear segment 60 (Fig. 4A), and with it the rod 56, until the head portion 58 has been brought to the releasing position shown in Fig. 4B. This frees the retaining rod 57 which is then pulled downwardly by the spring 55 62, thereby moving the wall gripping member 51 into engagement with the wall of the bore hole, as shown in Figure 3. At this time, the compression spring 63 (Fig. 4C) moves the gear segment 60 upwardly out of engagement with the gear 75 and the torque spring 64 immediately rotates it 60 back to its initial position.

In the downward movement of the retainer rod 57, the actuator 77 thereon engages the arm 78, thereby moving the latch 78a out of the recess 65 79 in the rod 38 (Fig. 3). This releases the rod 38 so that it can move downwardly under the weight of the chamber 17 and the motor 18 as soon as the tension on the cable 30 is released. Downward movement of the retainer rod 57 also 70 causes the actuator 102 thereon (Fig. 8) to close the switch contacts 101 momentarily, indicating to the operator at the surface that the sequence of operations has been initiated.

The cable 30 is then slackened off to permit the 75 block 33 to slide in the guide plates 45 under

the weight of the motor 18 until the bit 35 on the drilling and sampling means 34 extends through an aperture 110 and engages the side wall of the formation (Fig. 6). Continued operation of the motor 18 causes the drilling and sampling means to advance into the formation. It will be noted that the drill pressure is determined by the weight of the motor 18 and its mounting and is substantially constant.

It will be noted that while the drilling and sample taking operation proceeds, the pawl 69 (Fig. 2) moves downwardly against the teeth 108 on the arm 70, without turning the arm 70, although the stop arm 71 moves downwardly away from the arm 72. Hence, the rear portions 95a of the guide plates 45 remain in the locked position shown in Fig. 1.

When the desired length of core has been cut, the actuator 103 on the rod 38 (Fig. 8) closes the contacts 101, changing the reading of the ammeter A at the surface and indicating this fact to the operator at the surface. The operator then preferably stops the motor and pulls up on the cable 30 to raise the housing 17 within the body portion 11.

It will be apparent that as the supporting cable 30 is raised, the pawl 69 will tend to rotate the arm 70 (Fig. 2) in a clockwise direction, to the position shown in Figure 7, the stop member 71 being some distance below the arm 72. This releases the rear portions 95a of the guide plates 45 and pulls the pins 41 on the block 33 downwardly. As a result, torque is applied to the core 93 about the point where it is attached to the formation so that it is broken off at the point of maximum penetration. It is then held in place within the drilling and sampling means 34 by any suitable retaining means, as described above.

The dropping of the rear portions 95a of the guide plates 45 simultaneously causes the actuator 86 to move into engagement with the member 85 (Fig. 6) and to eject one of the balls 83 through the opening 90 into the core receiving magazine 81.

As raising of the cable 30 is continued, the block 33 is withdrawn into the body portion 11 and the head member 92 of the ejecting means 91 forces the sample downwardly into the funnel 82 which directs it into the core receiving magazine 81 to a position above the spherical ball 83.

The apparatus is preferably so designed that some time before the drilling and sampling means 34 has reached its point of maximum penetration, the head 58 on the rod 56 moves into the proper position to be retained by the spring detents 61. Accordingly, by continued pulling on the cable 30, the retaining rod 57 is pulled upwardly against the spring 62, permitting the wall gripping member 51 to be brought back within the apparatus. During this operation, the actuator 17 on the retaining rod 57 becomes disengaged from the arm 78 so that the latch 78a reenters the recess 79 in the shaft 68 locking the apparatus in the inoperative position, as shown in Figure 1.

As the rod 38 is raised during the lifting of the cable 30, the stop arm 71 (Fig. 7) moves upwardly and engages the arm 72, thus moving the cam 66 into its initial position, as shown in Figure 2, thus locking the guide plates 45 in their initial assembled position.

From the foregoing it will be understood that the invention provides highly effective apparatus for obtaining samples from the side wall of a bore hole drilled into the earth. By providing a sample receiving magazine for the cores, together

with core ejecting means on the drilling and sample receiving means, as many cores can be taken as can be accommodated by the magazine. Further, by automatically inserting a marker in the core receiving magazine at each sample taking operation, positive identification of the several cores taken can be readily effected. In addition, the sample cut may be of any desired length since it may be broken off at any time after the drilling operation has begun, merely by lifting the supporting cable.

It will be further understood that the operator at the surface can readily follow the sequence of operations in the bore hole by virtue of the novel signaling means provided in the apparatus. Also, the breaking and ejection of the core, the insertion of the marker and the resetting of the apparatus are all effected merely by raising the supporting cable.

While several representative embodiments of the invention have been described above, the latter is not intended to be limited thereto but is susceptible of numerous changes in form and detail within the scope of the appended claims.

25 I claim:

1. In sample taking apparatus for use in bore holes, the combination of a support movable through the bore holes, core barrel means carried by said support and rotatable relatively thereto for cutting a sample out of the side wall of a bore hole, means for rotating the core barrel means, sample storing means carried by said support, and means for transferring a sample from said sample cutting means to said sample storing means.

2. In sample taking apparatus for use in bore holes, the combination of drilling and sampling means, a support movable in the bore hole, motive means carried by the support for rotating the drilling and sampling means, means carried by the support for breaking off, at substantially its place of attachment to a formation, a sample drilled out of a formation, sample storing means carried by the support, and means for transferring a sample from said drilling and sampling means to said sample storing means.

3. In sample taking apparatus for use in bore holes, the combination of a support movable through the bore hole, core barrel means for cutting a sample out of the side wall of a bore hole, said core barrel means being rotatable relatively to said support, sample storing means carried by said support, means for transferring a sample from said sample cutting means to said sample storing means, and means for associating a marker with a formation sample for purposes of identification.

4. In sample taking apparatus for use in bore holes, the combination of rotatable core barrel drilling and sampling means, means for breaking off a sample drilled out of a formation, sample storing means, means for transferring a sample from said drilling and sampling means to said sample storing means, and means responsive to said sample breaking means for associating a marker with a formation sample for purposes of identification.

5. In sample taking apparatus for use in a bore hole, the combination of a support adapted to be lowered into a bore hole by a cable, drilling and sampling means slidably mounted in said support, and means rendered operative by pulling on said cable for applying a transversely directed force to said drilling and sampling means so as to apply a torque to a sample cut from a forma-

2,599,405

9

tion, about the base thereof, thereby breaking off said sample cut from a formation.

6. In sample taking apparatus for use in a bore hole, the combination of a support adapted to be lowered into a bore hole by a cable, drilling and sampling means slidably mounted in said support, means rendered operative by pulling on said cable for applying a transversely directed force to said drilling and sampling means so as to apply a torque to a sample cut from a formation, about the base thereof, thereby breaking off said sample cut from a formation, and means operated by pulling on said cable for rendering said force applying means inoperative.

7. In sample taking apparatus for use in a bore hole, the combination of a support adapted to be lowered into a bore hole by a cable, drilling and sampling means slidably mounted in said support, means rendered operative by pulling on said cable for applying a force to said drilling and sampling means to break off a sample cut from a formation, sample storing means, means operated by pulling on said cable for transferring a sample from said drilling and sampling means to said sample storing means, and means responsive to said force applying means for associating marker means with a sample for purposes of identification.

8. In sample taking apparatus for use in a bore hole, the combination of a support adapted to be lowered into a bore hole by a cable, drilling and sampling means slidably mounted in said support and having a connection to said cable, motive means for operating said drilling and sampling means, means rendered operative by pulling on said cable for applying a force to said drilling and sampling means to break off a sample cut from a formation, sample storing means, means operated by pulling on said cable for transferring a sample from said drilling and sampling means to said sample storing means, and means responsive to said force applying means for associating marker means with a sample for purposes of identification.

9. In sample taking apparatus for use in a bore hole, the combination of a support adapted to be lowered into a bore hole by a cable, releasable means for anchoring said support at a given level in a bore hole, drilling and sampling means slidably mounted in said support and having a connection to said cable, motive means for operating said drilling and sampling means and for releasing said anchoring means, means rendered operative by pulling on said cable for apply-

10

ing a force to said drilling and sampling means to break off a sample cut from a formation, sample storing means, means operated by pulling on said cable for transferring a sample from said drilling and sampling means to said sample storing means, means responsive to said force applying means for associating marker means with a sample for purposes of identification, and means operated by pulling on said cable for retracting said anchoring means.

10. In sample taking apparatus for use in a bore hole, the combination of drilling and sampling means adapted to be advanced into the side wall of a bore hole and to be retracted therefrom, means for applying a force to said drilling and sampling means to break off a core cut from a formation, a sample receiving magazine, means for transferring a sample from said drilling and sampling means to said magazine when the former is retracted from a formation, a second magazine, marker means in said second magazine, and means operated by said force applying means for transferring marking means from said second magazine to said core receiving magazine.

11. In sample taking apparatus adapted to be lowered into a bore hole on a cable, the combination of guide means, drilling and sampling means slidable in said guide means, and means cooperating with said guide means and rendered operative by pulling on said cable for applying a force thereto in a direction transversely with respect to the direction of sliding movement of the sampling means in the guide means, thereby to apply sufficient torque to the sample cut from a formation, about the base thereof, as to break off said sample.
